(57) CLAIM

The ornamental design for a tankless water heater housing, as shown and described.

DESCRIPTION

FIG. 1 is a front perspective view of the tankless water heater housing of the new design;

FIG. 2 is a back perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a back view thereof;

FIG. 9 is a front perspective view thereof with the front housing door in an open position;

FIG. 10 is a top view thereof with the front housing door in an open position; and,

FIG. 11 is a front view thereof with the front housing door in an open position.

In the figures, features shown by broken lines are for illustrative purposes only and form no part of the claimed design.
